United States Patent Office

Des. 183,094
Patented June 24, 1958

183,094

MONEY BOX OR SIMILAR ARTICLE

Edwin T. Heath and Roy I. Gandy, Macon, Ga., assignors to Heath-Gandy Corporation, Macon, Ga., a corporation of Georgia

Application August 29, 1957, Serial No. 47,544

Term of patent 14 years

(Cl. D34—11)

Fig. 1 is a perspective view of a money box or similar article, showing our new design.

Fig. 2 is a fragmentary side elevational view, the covering being partly broken away and cross-sectioned, the opposite side having substantially the same appearance; and

Fig. 3 is a rear elevational view thereof.

We claim:

The ornamental design for a money box or similar article, as shown and described.
